Patented March 28, 1905.

UNITED STATES PATENT OFFICE.

MARCUS T. GOLDSMITH, OF NEW YORK, N. Y.

DESIGN FOR A BACK FOR HAND-MIRRORS, BRUSHES, OR SIMILAR ARTICLES.

SPECIFICATION forming part of Design No. 37,382, dated March 28, 1905.

Application filed February 9, 1905. Serial No. 244,973. Term of patent 14 years.

To all whom it may concern:

Be it known that I, MARCUS T. GOLDSMITH, a subject of the Czar of Russia, and a resident of the city of New York, borough of the Bronx, 5 in the county and State of New York, have invented a new, original, and ornamental Design for a Back for Hand-Mirrors, Brushes, or Similar Articles, reference being had to the accompanying drawing, in which the figure is a 10 rear face view of a hand-mirror, showing the design.

I claim as new and desire to secure by Letters Patent—

The ornamental design for a back for hand-mirrors, brushes or similar articles, as shown. 15
